(57) **CLAIM**

The ornamental design for an electrical socket as shown and described.

DESCRIPTION

FIG. 1 is a right, front, top perspective view of an electrical socket in an embodiment showing my new design; FIG. 2 is a left, rear, bottom perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; and, FIG. 8 is a bottom plan view thereof.

In the drawings, the broken lines illustrate portions of the electrical socket that form no part of the claimed design.
